UNITED STATES PATENT OFFICE

CURT USCHMANN, OF GLENDALE, CALIFORNIA, ASSIGNOR TO CONTINUOUS RAIL CROSSING CORPORATION, OF RENO, NEVADA, A CORPORATION OF NEVADA

RAIL CROSSING

Application filed April 3, 1929. Serial No. 352,122.

My invention relates to crossings at the intersection of two or more railroad tracks and is particularly related to the type of crossing disclosed in Patent Number 1,169, 5 196, to Luther Sadler et al. entitled Railroad crossings. As therein disclosed, a turntable is disposed at the intersection of a pair of rails to provide selectively, a passage along the rails to one of the intersecting tracks.

It is an object of my invention to provide a simple and rugged means for operating the usual turntable.

Another object of my invention is to provide a simple and rugged means for positively locking the turntable in any one of the positions for alignment.

Another object of my invention is to provide a rail intersection of such a character that the passage of other vehicles and of 20 pedestrians is facilitated.

A further object of my invention is to provide a form of operating mechanism totally enclosed within a housing to protect it from tampering or damage.

25 A further object of my invention is to provide a rail crossing device which is not liable to be clogged inadvertently.

My invention possesses other advantageous features, some of which with the foregoing will be set forth at length in the following description where I shall outline in full the form of the railroad crossing of my invention, which I have selected for illustration in the drawings accompanying and 35 forming part of the present specification.

In said drawings I have shown one form of railroad crossing embodied in my invention, but it is to be understood that I do not limit myself to said form, for the invention, as set forth in the claims, may be embodied in 40 a plurality of forms.

In said drawings:

Figure 1 is a plan view of the crossing of my invention with the cover plates removed to show the actuating mechanism, and with a portion of the device cut away to show the turntable actuator.

Figure 2 is a section of the device shown in Figure 1 along the broken section line 50 2-2 of Figure 1 with the cover plate in

place. Figure 3 illustrates another embodiment of my device with the cover plates removed and sections of the device cut away to show the turntable actuator and the means for locking the turntables in position. 55

Figure 4 is a section thru the device of my invention shown in Figure 3 along the broken section line 4-4 with the cover plate in place.

Rail crossings of a character similar to that of my invention has usually depended for their operation upon a complicated system of levers or of levers, gears and racks. These have been placed in the road bed along the rails and so are exposed to various undesirable hazards among which are the following: tampering which, even if it is not malicious, is dangerous; to damage from any one of many possible sources; to the action of the weather which is liable to render 60 them inoperable; and to clogging by the ballast of the road bed. 65

Furthermore it is extremely difficult to construct a smooth crossing over the usual rail intersection for pedestrians or for other vehicles. This I have likewise provided for.

The locking devices, for maintaining the crossings in some one particular position, have likewise been more or less complicated and, at the same time, they have been exposed to the same hazards as the crossing mechanism. It is the broad object of the rail crossing of my invention to materially mitigate or overcome these hazards and 80 objections. 85

In the form of my invention disclosed in the drawings, particularly in Figures 1 and 2, I provide a structure 6 which may be suitably disposed at the intersection of a pair of rails 7 and 8. At the intersection 80 of each of the rails I provide a casing 11 which I preferably form integrally with the intersecting rails although it may be separate therefrom. Each of the casings 11 is preferably cylindrical in interior contour 90 to receive a turntable 12 which is adapted to rotate within the casing 11. Each turntable 12 has a diametral groove 13 across the upper face 14 thereof. The turntable 95 is adapted for rotation within the casing 100

from alignment with one rail to alignment with the other rail and the groove is suitably dimensioned to allow the ready passage of a wheel flange along the rail with which it is aligned.

6 Means are provided for suitably rotating the turntables 12. Each turntable is usually provided with the non-circular extension 16 on which a lever arm 17 is suitably retained as by means of the lock nut 18. To the free end of the lever arm 17 one end of a turnbuckle 21 is attached by means of a bolt 22. The other end of the turnbuckle 21 is preferably formed integrally with an arm 23. Suitable means for locking the turnbuckle in position, when the length of the arm 23 is correctly adjusted, are provided in the lock nuts 25.

20 The several arms 23 are preferably attached to the peripheral portion of a centrally disposed stellated body 24 by means of the bolts 26. The points of attachment of the several arms are preferably spaced about 90 degrees apart around the circumference of the body. The body 24 is suitably adapted for rotation and is conveniently provided with a circular extension 27. A plate 28 is usually provided, within and upon which the body may be rotated. To 25 accomplish the rotation of the body a portion of the extension 27 is conveniently made non-circular and a lever arm 31 is retained thereon by means of a lock nut 32. The lever arm 31 is attached to any suitable operating means but I preferably use a solenoid 33 to accomplish the actuation in combination with other electrical means.

40 It is thus seen that with the grooves 13 of the turntable in alignment with the rails 8, as in Figure 1, rotation of the actuator 24 thru an angle of 90 degrees in a counter clockwise direction by energizing of the solenoid will align the grooves with the other pair of rails 7. Correspondingly, a 45 rotation of 90 degrees in a clockwise direction, when the grooves are in alignment with the rails 7, will bring the grooves into agreement with the rails 8.

To accomplish further objects of my invention I have preferably provided means 50 for totally enclosing the whole of the operating mechanism. Thus a central body 36 which is adapted to contain the several levers and centrally disposed stellated actuator 24 is provided beneath the intersecting rails. A base 37 is disposed below the body 36 and is suitably adapted to the type of mechanism actuating the crossing. The bodies 36 and 37 are suitably attached to the 55 intersecting rails, by means of stud bolts 38, to provide a functionally integral structure. The base body is suitably formed to retain its position on a foundation and, for this reason, among others, the webs 39 are 60 provided. The upper portion of the base

body 37 is preferably provided with the inwardly extending flanges 40 upon which the plate 28 is conveniently positioned by the shoulder 42.

To provide against any of the possible hazards attendant upon these crossings, which I have previously mentioned, I provide suitable cover plates 43 and 44 which are adapted to be disposed over the mechanism of the device and retained in position on the several shoulders 46 and 47 respectively formed upon the several intersecting rails. Either one or both of these covers may be retained in place by some suitable locking means. The structure, when assembled as a whole, is substantially proof against the entrance of any foreign matter.

Preferably, to insure that all the turntables 12 are maintained in either of the extreme alignment positions, I provide means for locking them in either of these positions. In Figures 3 and 4 I have shown a convenient way of accomplishing this in combination with the device of my invention previously described in particular in Figures 1 and 2. I provide, as means for expediently accomplishing this object, among others, the stellated actuator body 61 which conveniently has a circular extension 62. This extension is usually adapted to be independently revolved in the turntable actuator body 24 which is likewise usually fitted to receive this extension and permit its rotation therein. The lower portion of the extension 62 is preferably made non-circular and a lever 63 retained thereon by means of a lock nut 64. Any form of operating means may be attached to the lever 63 but I preferentially employ a solenoid 66 for controlling and operating the actuator body 61.

45 Several outwardly extending arms 71 are conveniently attached to the central actuator 61 by means of studs 72 which retain them in the several supporting recesses 73. Each arm is adapted to be received in suitable recesses 76 and 77 provided in the turntable 12 to agree with its extreme alignment positions. A passage 78 is provided in the casing 11 to guide correctly the passage of the arm 71 into either of the recesses 76 and 77.

The lengths of the several arms 71 are expediently varied by means of the turnbuckles 79. The lock nuts 80 and 81 serve to ensure the preservation of any desired length of the arms 71 by locking the turnbuckle in position.

With the turntables locked in position as in Figure 3 it is readily seen that actuation of the solenoid 66 to turn the actuator 61 in a counter clockwise direction will release the locking arms from engagement with the turntables leaving them free to rotate. Energizing of the solenoid 33 to rotate the actu-

ator 24 thru 90 degrees in a clockwise direction will position the turntables in alignment with the rails 8. The solenoid 61 is then energized in a reverse direction and the turntables locked in alignment with the rails 8.

I claim:

1. A railroad crossing comprising intersecting rails, a casing at the intersection of said rails, a turntable in said casing adapted to rotate therein between two extreme positions, said turntable having a groove adapted to be aligned in extreme position with either of said rails, an actuator centrally disposed with respect to said intersecting rails, linkage connecting said actuator with said turntable, a second actuator mounted upon said first actuator, and means attached to said second actuator for locking said turntable in either of said extreme positions.
2. A railroad crossing comprising intersecting rails enclosing a central space, means for selectively forming a continuous rail crossing of one corresponding pair of rails, means disposed within said central space for selectively operating said crossing means, means for locking said crossing forming means, means disposed within said central space for selectively operating said locking means, and a housing enclosing both of said operating means.

3. A railroad crossing comprising intersecting rails enclosing a central space, a plurality of casings, one of said casings being disposed at each of the intersections of said rails, a plurality of turntables, one in each of said casings and adapted to rotate therein for forming a continuous rail crossing of each corresponding pair of rails, and a support for said crossing secured to said casings; said support including a body having a chamber therein communicating with said central space, and an actuator disposed in said chamber for selectively operating said turntables between two extreme positions.

4. A railroad crossing comprising intersecting rails enclosing a central space, a plurality of casings, one of said casings being disposed at each of the intersections of said rails, a plurality of turntables, one in each of said casings and adapted to rotate therein for forming a continuous rail crossing of each corresponding pair of rails, and a support for said crossings secured to said casing; said support including a body having a chamber therein communicating with said central space, an actuator disposed in said chamber for selectively operating said turntables between two extreme positions, a second actuator mounted upon said first named actuator, and means attached to said second actuator for locking said turntables in either of their extreme positions.

5. In combination with a railroad crossing including intersecting rails and means for selectively forming a continuous rail crossing of one corresponding pair of rails, a support for said crossing comprising a central body and a base body below said intersecting rails and secured thereto; each of said bodies having a central chamber in communication with one another and in which said means are disposed, and inwardly extending flanges on said base body for supporting said means in said chamber.

In testimony whereof, I have hereunto set my hand.

CURT USCHMANN.
